UNITED STATES PATENT OFFICE.

MILlicent GORDON, OF WEST KENSINGTON, LONDON, ENGLAND.

HAT-FASTENER.

SPECIFICATION forming part of Letters Patent No. 752,288, dated February 16, 1904.

Application filed July 9, 1903. Serial No. 164,218. (No model.)

To all whom it may concern:

Be it known that I, MILlicent GORDON, a subject of the King of Great Britain, residing at West Kensington, London, England, have 5 invented certain new and useful Improvements in Ladies' Hat-Fastening Devices, of which the following is a specification, such as will enable those skilled in the art to which it appertains to make and use the same.

10 The object of this invention is to provide an improvement for holding a lady's hat on her head; and with this and other objects in view the invention consists of a device of the class specified constructed as hereinafter described

15 and claimed.

The invention is fully disclosed in the following specification, of which the accompanying drawings form a part, in which the separate parts of my improvements are designated 20 by suitable reference characters in each of the views, and in which—

Figure 1 is a perspective view of my improved hat-holding device; Fig. 2, a plan view of a blank from which the same is made; Fig. 25 3, a section on the line 3 3 of Fig. 1; Fig. 4, a perspective view of a modification, and Fig. 5 a similar view of another modification.

In the practice of my invention, as shown in Figs. 1 to 3, inclusive, I employ a curved 30 flange or coronet a , which is shaped something like a horseshoe and comprises a semicircular back portion a^2 and side portions a^3 and in which is formed or placed a comb b , the teeth of which project forwardly in the same directions as the side portions a^3 . This device, as shown in Figs. 1 to 3, is preferably made from a sheet of any suitable material stamped into the form as shown in Fig. 2, the curved back portion a^2 thereof consisting of separate sections a^4 , separated by V-shaped recesses a^5 , and after the blank shown in Fig. 2 has been stamped out it may be bent into the position shown in Fig. 1, and the separate back sections a^4 may be connected by stitching, as 45 shown at a^6 , or in any desired manner. The material may consist of celluloid, artificial ivory, metal, or any other suitable material,

and the device may also be made of tortoise-shell, if desired, and may be made entirely in one piece, as shown in Fig. 4, or the comb portion b may be hinged to the back portion, as shown at e in Fig. 5, and various forms may be given to the side portions a^3 , and in each form of construction the side portions a^3 are provided with a number of perforations 50 or openings f , through which in practice a hat-pin g may be passed, as shown in Fig. 1.

The device may be ornamented in any desired way, and the back portion a^2 when formed of one piece may be formed into a scroll or of 55 any desired shape.

In this manner I construct a semicircular perforated corona, the perforated portion of which is perpendicular relatively to the top or crown of the head when in use, and the 60 teeth of the comb part thereof are in practice inserted into the hair above the forehead. This forms a firm support over which the hat is placed and through which is passed the hat-pin g , and a number of hat-pins may be employed, if desired.

I may in some cases dispense with hat-pins by forming the corona of elastic material fitting or pressing upon the interior of the hat-crown and having a surface more or less roughened or serrated.

Having fully described my invention, what I claim as new, and desire to secure by Letters Patent, is—

An attaching device for ladies' hats comprising a comb provided with a corona or rim at right angles thereto, and consisting of front and side portions, the side portions being finely perforated so as to permit a hat-pin to pass therethrough at any point, substantially 80 as shown and described.

In testimony that I claim the foregoing as my invention I have signed my name, in presence of the subscribing witnesses, this 23d day of June, 1903.

MILlicent GORDON.
